Attorneys

UNITED STATES PATENT OFFICE.

CARY FRANCISCO, OF PORTERVILLE, CALIFORNIA.

STITCH CLIPPER FOR SCISSORS.

1,423,791.

Specification of Letters Patent. Patented July 25, 1922.

Application filed June 22, 1920. Serial No. 390,757.

To all whom it may concern:

Be it known that I, CARY FRANCISCO, a citizen of the United States, residing at Porterville, in the county of Tulare and State of California, have invented certain new and useful Improvements in Stitch Clippers for Scissors, of which the following is a specification.

This invention relates to scissor attachments and the primary object of the invention is to provide an improved means for associating a knife blade with a pair of scissors, so as to facilitate the ripping of seams or the like when necessary.

Another object of the invention is to provide an improved combination tool for dressmakers or the like, which obviates the necessity of providing separate instruments for cutting the garment and for ripping the seams thereof.

A further object of the invention is to provide means for utilizing a single spring for holding the knife blade in its open operative position and in its closed inoperative position, the spring being so arranged as to absolutely prevent the accidental swinging movement of the knife blade when the same is in either one of its positions.

A further object of the invention is to provide a pair of scissors having a stitch ripping knife associated therewith in an approved manner so that a neat non-bulky article will be provided and which will add to the appearance of the scissors rather than detracting from the appearance thereof.

With these and other objects in view, the invention consists in the novel construction, arrangement and formation of parts as will be hereinafter more specifically described, claimed and illustrated in the accompanying drawings, forming a part of this specification, in which drawings:

Figure 1 is a side elevation of the improved combined scissors and stitch ripping knife.

Figure 2 is an enlarged fragmentary elevation of the combined scissors and stitch ripping knife, parts of the same being shown in section, to illustrate the means of associating the knife with the scissors, and

Figure 3 is an enlarged transverse section taken on the line 3—3 of Figure 2.

Referring to the drawings in detail, wherein similar reference characters designate corresponding parts throughout the several views, the letter A generally indicates a pair

of scissors, and B the stitch ripping knife associated therewith.

The scissors A are of the usual or any preferred configuration and include the cutting blades 5, the rearwardly extending shanks 6 and 7 and the finger receiving loops 8 and 9. The blades are pivotally connected adjacent to their rear ends in the usual manner, by a pin or rivet 10. The shank 7 of one of the blades is preferably formed slightly wider than ordinary and the lower surface is provided with an inwardly extending groove 12 which is adapted to form the seat for the stitch ripping knife B. The forward portion of the upper wall of the groove 12 forming the seat is provided with a recess or notched portion 13 which is adapted to form a seat for the latching spring 14. The portion of the shank 7 directly below the recess or notched portion of the groove 12 is provided with a pair of depending ears 15, which form supports for the pivot pin 16 on which the ripping blade B is mounted.

The stitch ripping blade B may be of any desired configuration and is preferably formed of a good grade of steel and includes the longitudinally extending cutting edge 17. One end of the blade B is provided with the shank or hilt portion 18, the opposite faces of which are arranged in parallel relation to one another and are adapted to form the engaging faces 19 for the latching spring 14.

When the blade B is in its inoperative position, the same is swung on the pivot pin 16 until the sharp cutting edge 17 thereof is positioned in the longitudinally extending groove 12 formed in the shank 7. The spring 14 which is of the leaf type engages the flat surface of the shank thereof and absolutely precludes accidental swinging movement of the same on the pivot pin 16. The terminals of the spring 14 are fitted in the corners of the recessed or notched portion 13, and the body of the spring is curved arcuately as can be readily seen. The opposite faces of the blade B adjacent to the non-cutting edge thereof is provided with finger nail recesses 20 which are adapted to lie below the shank 7 when the blade is in its inoperative position, so as to facilitate the opening of the blade when necessary. A portion of the shank 7 in advance of the pivot pin 16 is provided with a longitudinally extending groove 21 in which the non-cutting edge of

the knife blade is adapted to fit when the blade is swung to its operative position. The provision of the groove 21 absolutely precludes lateral movement of the blade B when the same is in its extended operative position and thus eliminates all strains on the pivot pin 16. The forward end of the blade B adjacent to its cutting edge is provided with the finger nail receiving recesses 22, which permit the ready grasping of the knife blade when it is desired to close the same.

The position of the knife blade B is such as to permit the most effective using thereof and it can be seen that the handle or finger loops of the scissor will form the handle for the knife blade B.

From the foregoing description, it can be seen that an improved combination tool has been provided, which is especially adapted for dress makers or the like in which the cutting of garments and the ripping of seams may be accomplished with the same instrument and thus eliminate the necessity of providing separate tools for each one of the operations.

Changes in details may be made without departing from the spirit or scope of this invention; but,

I claim:

30 1. In combination, a pair of scissors having a longitudinally extending groove formed in the outer edge of one shank of one of its blades, a pair of depending ears formed on said shank intermediate the terminals of the groove, the inner wall of said groove having an inwardly extending notch positioned directly inwardly of said ears, a knife blade, a pivot pin connecting said knife blade to said ears, the shank of said knife blade having its edges arranged in parallel relation and flattened to form bearing bases, and an arcuate leaf spring having its terminals fitted in the opposite corners of said recessed portion and arranged to engage the flattened faces of the shank of the knife. 45

2. In combination, a pair of scissors having a longitudinally extending groove formed in the outer edge of one shank of one of its blades, a pair of outwardly extending ears formed on said shank intermediate the terminals of the groove, the inner wall of said groove having an inwardly extending notched portion, an arcuate spring having its terminals fitted in the corners of said notched portion, a pivot pin carried by said ears, a knife blade mounted upon said pivot pin, the knife blade being adapted to fit in said groove when in its opened or closed position, the knife blade having parallel flattened faces arranged on the opposite sides of the pivot pin arranged to engage the arcuate body of the leaf spring when the blade is in its opened or closed position, said knife blade having finger nail receiving recesses formed therein adjacent to its opposite longitudinal edges. 50 55 60 65

MRS. CARY FRANCISCO.
